UNITED STATES PATENT OFFICE.

CHARLES J. KINDEL, OF GRAND RAPIDS, MICHIGAN, ASSIGNOR TO GRAND RAPIDS TRUST COMPANY, OF GRAND RAPIDS, MICHIGAN.

DIVANETTE.

1,270,742.

Specification of Letters Patent. Patented June 25, 1918.

Application filed February 19, 1912, Serial No. 678,556. Renewed March 14, 1918. Serial No. 222,512.

To all whom it may concern:

Be it known that I, CHARLES J. KINDEL, a citizen of the United States, residing at Grand Rapids, in the county of Kent and State of Michigan, have invented new and useful Improvements in Divanettes, of which the following is a full, clear, concise, and exact description, reference being had to the accompanying drawing, forming a part of this specification.

This invention relates to improvements in folding sofa-beds; and the principal objects of the invention are to simplify the construction, whereby the parts may be readily folded or closed and unfolded or opened for use as a bed and when closed will occupy a minimum space; to produce an improved sofa-bed having means for locking the folding bed-sections while being manipulated; and to provide a sofa-back independently adjustable with respect to the seat, and means for holding the back in any of its adjusted positions.

Other objects and advantages of the invention will appear in the following description, and the novel features thereof will be more particularly pointed out in the appended claims.

Referring to the drawings—

Figure 1 is a side elevation of a sofa-bed embodying my invention, the adjacent end of the frame being removed for the purpose of clearness, and the bed being shown unfolded so as to serve as such;

Fig. 2 is a plan view of the same;

Fig. 3 is a view similar to Fig. 1, the bed being shown folded and the structure adapted to serve as an ordinary sofa;

Fig. 4 is a sectional view taken on the line 4—4 of Fig. 1;

Fig. 5 is a sectional view taken on the line 5—5 of Fig. 4; and,

Fig. 6 is an elevation of the intermediate supporting-leg.

Similar numerals of reference indicate similar parts throughout the drawings.

The sofa-frame comprises opposite ends 1, and connecting back-board 2; and as a whole, the structure may be of any usual design. In the bottom of the sofa-frame is a base-frame 3, preferably formed of angle-iron and conforming to the contour and dimensions of said sofa-frame. This base-frame may be supported in position within the sofa-frame in any desired manner, but

preferably by means of clips 4, secured to the ends 1, adjacent the back-board 2, and by uprights 5, located adjacent the front of the sofa-frame, and to which the base-frame is secured as at 6. These uprights 5 may be secured in position by any means desired, but preferably by means of securing-plates 7, secured to the ends 1, having angular or hook-shaped projections 8, which enter similarly located openings 9, formed in the uprights or standards 5. The uprights or standards 5, which may be and preferably are formed of angle-iron, are connected at their lower ends by the bar 10, (see dotted lines Figs. 1 and 3) also of angle iron, said bar being so disposed that its vertical upper flange will pass in rear of a keeper 11, secured to the rear face of the front-rail 12 of the sofa-frame, in which position it may be securely locked by cams 13, pivoted to the rail 12, and adapted to be turned upward so as to bind against the underside of said bar.

A sectional folding bed-frame or mattress-support is supported by the base-frame 3, and consists of a rear-section 14, a rear connecting-section 15, a middle-section 21, a front connecting-section 23, and a foot-section 25, these sections being articulated or pivoted together in the order mentioned. The rear end of the rear-section 14, is supported by links 17, pivoted at their upper ends, as at 18, to the section 14, and at their lower ends, as at 19, to the base-frame 3, the latter pivots preferably being the same that secure the base-frame to the clips 4. The front edge of the section 14, is pivoted, at 16, to the adjacent edge of the section 15, and the front edge of the latter is pivoted, at 20, to the upper ends of the uprights 5. The sections 14 and 15, uprights 5, and links 17, are arranged, as will be seen, entirely within the area of the sofa-frame, the links 17 being of such length that when the bed is unfolded for use it will be supported at a convenient height above the floor.

The middle-section 21 is pivotally connected at its rear edge to the uprights 5, the pivot 20 being utilized for this purpose, and said section may be provided near its outer or front edge and at its sides with a pair of depending arms 22, for a purpose hereinafter explained. The front connecting-section 23, is pivoted at its rear edge, as at 24, to the adjacent edge of the middle-section 21, and at its front edge, as at 26, 110

2
to the adjacent edge of the foot-section 25. It will be understood that these several sections are all preferably constructed of angle-iron, as is usual, have their side-bars overlapped, and are capable of being folded or breaking joint and yet are so limited in their outward pivotal movements that they will all lie in the same horizontal plane, such features being common to beds of this 5 class. It will be further understood that over the jointed frame thus formed there is stretched the mattress-supporting fabric 29, the same being of any desired construction and design.

10 15 The outer end of the foot-section 25 of the bed is supported by legs 30, pivotally connected at their upper ends, as at 31, to the opposite sides and near the free edge of the section. These legs are capable of 20 folding alongside the section to which they are pivoted, and are in the present instance locked in their unfolded or operative position by means of a pair of curved links 32, pivoted intermediate their ends, as at 33, to 25 the sides of the foot-section in advance of the legs. Near their lower ends the links are offset so as to pass the legs and below such offset portions are provided with slots 35, that engage and ride over pins or studs 34, projecting from the legs. The slots 35, 30 at their inner ends, are angularly disposed or offset, so that when the pins or studs 34 drop therein the legs are braced and locked in their operative position. At their upper 35 ends the links 32 curve rearward over the foot-section 25 and are fashioned to form hooks 38, which, when the foot-section is folded over and upon the middle-section 21, are designed to automatically engage with 40 studs 39 that project laterally from the sides of the said middle-section, whereby, as will be apparent these sections become securely locked together and capable of being turned as a whole during any further manipulation of the bed.

An intermediate supporting-leg 40, is pivoted at its upper end, as at 41, to a cross-bar 42, connecting the depending arms 22, of the middle-section 21, (see Figs. 1 and 50 6), and an angular link 43, is pivotally connected at its upper end, as at 44, to the front-bar 42, of the said middle-section, and near its lower or free end is slotted, as at 47, to engage a pin 46, projecting from 55 the leg 40. The upper end of the slot may be provided with an offset or angular portion 48, so that when such is occupied by the pin 46, the leg 40 becomes braced and locked in its operative or supporting position. 60 As will be apparent, by disconnecting the pin from the offset or angular portion of the slot 47, the leg will be free to be folded parallel with the middle-section and therefore out of the way of folding 65 the bed. When unfolded, the leg and its

bracing-link will automatically drop to an operative position of support.

The sofa-seat 49, is adapted to rest upon the middle-section when folded in sofa-form, and is connected to said middle-section by means of front and rear pairs of links 50 and 51 respectively, whereby, when the bed is opened, the said seat will assume a suspended position under the middle-section 21.

70 75 Assuming the parts to be in the position shown by full-lines in Fig. 1, and it is desired to close the bed whereby to convert the same to a sofa, as shown in Fig. 3, the operator raises the free-end of the foot-section 25 and with it the outer connecting-section 23, the latter breaking joint at the pivots 24. At the same time, the links 32 are disengaged from their locked positions with the legs 30 so as to permit the latter 80 to fold alongside the section 25. The sections 25 and 23 will now be in the position shown by dotted lines in Fig. 1. These two sections, 23, 25, now break joint at the pivots 26, the foot-section 25 being lowered toward and upon the middle-section 21, whereupon the hooks 38 of the links 32 will automatically engage with the pins or studs 39 of the middle-section, and thus the three sections 21, 23 and 25, will become rigidly 90 95 and securely locked and capable of turning together. These sections are now turned upon the pivots 20, thus causing the sofa-seat 49 to assume its operative position at the top of the bed. Further movement of 100 the partially folded bed in the same direction will cause the rear-section and the rear-connecting section to break joint at the pivots 16, the latter section assuming a vertical position between the uprights 5, and the 105 former section swinging downward and forward, during which movements it is guided by the supporting-links 17. To return the structure to bed-form will, of course, require but a mere reversal of the operation 110 described, and will be readily understood.

A flexible wall may be secured to the front edge of the seat 49 and the front rail 12 of the sofa-frame, so as to close from view the space between these two parts 115 when the seat is in its operative position.

The sofa-back, designated as 53, may be of any shape and construction and supported in any desirable manner. In this instance, however, it is adapted to be adjusted 120 and held in several positions. For this purpose, I may provide each end of the sofa-back with an attached securing-plate 54, pivoting to the upper ends of the same links 55, and to the lower ends somewhat longer 125 links 57. The links 55 and 57 are respectively pivoted to lugs or ears 56 and 58, projecting from the back 2 of the sofa-frame and arranged vertically opposite, and such lugs or ears may, as shown, be formed as in- 130

tegral parts of a securing-plate 59. As stated, the lower links are somewhat longer than the upper links, and the former are slotted, as at 61, near their lower ends, to receive the pins 60, projecting from the lugs or ears 58.

When the seat 49 is in the operative position shown in Fig. 3, the sofa-back will be positioned as shown in said figure; that is to say, suitably inclined to lend comfort and with its lower edge resting upon and overlapping the back edge of the seat so as to avoid any unsightly space therebetween. The back 53 is preferably of hollow construction, or, in other words, formed with a cavity in its rear side, which, in conjunction with a flexible apron 62, connected to the back and to the back-rail of the bed constitutes a pocket of considerable capacity and therefore capable of the reception and convenient storage of pillows and other bed appurtenances. If access to this pocket is desired, the sofa-back is swung into the position shown by dotted lines, Fig. 3, that is, upward and outward, the link-mechanism described permitting of this movement. When the bed is opened for use, the sofa-back may be adjusted to the position shown in Fig. 3, the links 55 and 57 not only permitting of such adjustment but also serving to retain the back when so adjusted, the upper links swinging vertically and rearwardly back of their pivot points.

It will be observed that the legs 30 being pivoted to the links 32 at that side of the pivots 33 of the latter opposite the free ends of the links where the hooks are located, will serve as weights for the links, whereby when the foot-section 25 carrying the links is brought to a substantially horizontal position above the middle-section 21, the tendency of the free ends of said links will be to swing rearward. When, however, the ends of the links, which, as shown, are rounded for the purpose, meet the studs or pins 39, they ride over the latter until the hooks are opposite the pins, when the weight of the legs causes the hooks to interlock with the pins. It will be apparent, therefore, that the locking of these parts is accomplished by a positive gravity operated locking-means.

It will also be apparent that by the employment of the front and rear connecting-sections, respectively numbered 23 and 15, the sections 14, 21 and 25, are spaced apart, the links 33 aiding to maintain this relation between the free end of the foot-section 25 and the middle-section 21. By providing these spaces between the sections, an ordinary mattress may be folded with the bed and stored between the sections below and under the sofa-seat within the base of the sofa-frame.

It will be observed that while the two

short connecting bed-sections 15 and 23 are designed herein as the rear-connecting section and the front-connecting-section, such is merely for convenience, for, as a matter of fact, the rear-connecting section 15 constitutes a part of the head-section while the front-section 23 constitutes a part of the foot-section, such head and foot-sections being made breakable or foldable, whereby to space the bed-sections a proper distance apart for the accommodation of the mattress, which, it will be understood, is folded with the sections within the sofa-frame. The rear-connecting section 15, it will be observed, is somewhat longer than the front-connecting section, this being for the purpose of enabling the foot-section 25 to be nested between the sections 21 and 14. The locking-means, in this instance, the links 37, coact with the front-connecting section 23 to support the foot-section at its front and rear and thus space the same from the sections 14 and 21. Variations may be made in the details of my invention without departing from the spirit of the same, so that I do not wish to be understood as limiting the invention to the precise details shown.

Having described my invention, what I claim is:

1. The combination, in a sofa-bed, of a plurality of folding bed-sections adapted to be extended and supported in bed-form or folded within the frame of the sofa, supporting legs for the outermost section, and a common means for locking the outermost section and the adjacent section together when folded and for locking the legs in operative position when said sections are unfolded.

2. The combination, in a sofa-bed, of a plurality of folding bed-sections adapted to be extended and supported in bed-form or folded within the frame of the sofa, supporting-legs for the outermost section, and a common means for automatically locking the outermost section and the adjacent section together when said sections are folded and for automatically locking the legs in their operative position when said sections are unfolded.

3. The combination, in a sofa-bed, of a plurality of folding bed-sections adapted to be extended and supported in bed-form or folded within the frame of the sofa, pivoted supporting-legs for the outermost section, links intermediately pivoted on the outermost section and terminating at their upper ends in engaging ends, loose connections between the lower ends of said links and the legs, and means on the adjacent section for engaging said engaging-ends of the links when the sections are folded.

4. The combination, in a sofa-bed, of a plurality of folding bed-sections adapted to be extended and supported in bed-form

1. The combination, in a sofa, of a sofa-frame, a mattress-support, a middle-section pivoted to the sofa-frame, a foot-section pivoted to the middle-section, and a head-section pivoted to the foot-section, the middle-section and foot-section being foldable over and upon the head-section, and means for locking the middle-section and foot-section together when the sections are folded.
2. The combination, in a sofa, of a sofa-frame, a mattress-support, a middle-section pivoted to the sofa-frame, a foot-section pivoted to the middle-section, and a head-section pivoted to the foot-section, the middle-section and foot-section being foldable over and upon the head-section, and means for locking the middle-section and foot-section together when the sections are folded, the means for locking being located on the middle-section and foot-section.
3. The combination, in a sofa, of a sofa-frame, a mattress-support, a middle-section pivoted to the sofa-frame, a foot-section pivoted to the middle-section, and a head-section pivoted to the foot-section, the middle-section and foot-section being foldable over and upon the head-section, and means for locking the middle-section and foot-section together when the sections are folded, the means for locking being located on the middle-section and foot-section, and further including a locking-member mounted on the middle-section and adapted to engage with the foot-section when the sections are folded.
4. The combination, in a sofa, of a sofa-frame, a mattress-support, a middle-section pivoted to the sofa-frame, a foot-section pivoted to the middle-section, and a head-section pivoted to the foot-section, the middle-section and foot-section being foldable over and upon the head-section, and means for locking the middle-section and foot-section together when the sections are folded, the means for locking being located on the middle-section and foot-section, and further including a locking-member mounted on the middle-section and adapted to engage with the foot-section when the sections are folded, the locking-member being located on the middle-section and adapted to engage with the foot-section when the sections are folded.
5. The combination, in a sofa, of a sofa-frame, a mattress-support, a middle-section pivoted to the sofa-frame, a foot-section pivoted to the middle-section, and a head-section pivoted to the foot-section, the middle-section and foot-section being foldable over and upon the head-section, and means for locking the middle-section and foot-section together when the sections are folded, the means for locking being located on the middle-section and foot-section, and further including a locking-member mounted on the middle-section and adapted to engage with the foot-section when the sections are folded, the locking-member being located on the middle-section and adapted to engage with the foot-section when the sections are folded.
6. The combination, in a sofa, of a sofa-frame, a mattress-support, a middle-section pivoted to the sofa-frame, a foot-section pivoted to the middle-section, and a head-section pivoted to the foot-section, the middle-section and foot-section being foldable over and upon the head-section, and means for locking the middle-section and foot-section together when the sections are folded, the means for locking being located on the middle-section and foot-section, and further including a locking-member mounted on the middle-section and adapted to engage with the foot-section when the sections are folded, the locking-member being located on the middle-section and adapted to engage with the foot-section when the sections are folded.
7. The combination, in a sofa, of a sofa-frame, a mattress-support, a middle-section pivoted to the sofa-frame, a foot-section pivoted to the middle-section, and a head-section pivoted to the foot-section, the middle-section and foot-section being foldable over and upon the head-section, and means for locking the middle-section and foot-section together when the sections are folded, the means for locking being located on the middle-section and foot-section, and further including a locking-member mounted on the middle-section and adapted to engage with the foot-section when the sections are folded, the locking-member being located on the middle-section and adapted to engage with the foot-section when the sections are folded.
8. The combination, in a sofa, of a sofa-frame, a mattress-support, a middle-section pivoted to the sofa-frame, a foot-section pivoted to the middle-section, and a head-section pivoted to the foot-section, the middle-section and foot-section being foldable over and upon the head-section, and means for locking the middle-section and foot-section together when the sections are folded, the means for locking being located on the middle-section and foot-section, and further including a locking-member mounted on the middle-section and adapted to engage with the foot-section when the sections are folded, the locking-member being located on the middle-section and adapted to engage with the foot-section when the sections are folded.
9. The combination, in a sofa, of a sofa-frame, a mattress-support, a middle-section pivoted to the sofa-frame, a foot-section pivoted to the middle-section, and a head-section pivoted to the foot-section, the middle-section and foot-section being foldable over and upon the head-section, and means for locking the middle-section and foot-section together when the sections are folded, the means for locking being located on the middle-section and foot-section, and further including a locking-member mounted on the middle-section and adapted to engage with the foot-section when the sections are folded, the locking-member being located on the middle-section and adapted to engage with the foot-section when the sections are folded.
10. The combination, in a sofa, of a sofa-frame, a mattress-support, a middle-section pivoted to the sofa-frame, a foot-section pivoted to the middle-section, and a head-section pivoted to the foot-section, the middle-section and foot-section being foldable over and upon the head-section, and means for locking the middle-section and foot-section together when the sections are folded, the means for locking being located on the middle-section and foot-section, and further including a locking-member mounted on the middle-section and adapted to engage with the foot-section when the sections are folded, the locking-member being located on the middle-section and adapted to engage with the foot-section when the sections are folded.

and automatically operated means for locking said legs and said locking-member together.

8. The combination, in a sofa-bed, of a sofa-frame, a mattress-support, comprising a foldable head-section mounted in the sofa-frame, a middle-section supported rotatably upon and at the front of the sofa-frame and pivoted to the head-section, and a foldable foot-section pivotally secured to the middle-section and foldable over and upon said middle-section and these two sections rotatable upon the sofa-frame and foldable upon the head-section, whereby, when said mattress-support is thus folded, the said foot-section is positioned between its two companion sections, a sofa-seat movably mounted upon the middle-section, and means for lowering the folded mattress-support within the base of the sofa-frame and beneath the seat.

9. The combination, in a sofa-bed, of a sofa-frame, a mattress-support, comprising a foldable head-section mounted in the sofa-frame, a middle-section pivotally secured to the head-section, a foldable foot-section pivotally secured to the middle-section and foldable over and upon said middle-section and these two sections foldable over and upon the head-section, whereby, when said mattress-support is thus folded, the said foot-section is positioned between its two companion sections, a sofa-seat, means for movably supporting the same upon the middle-section when the latter is folded and for suspending it when unfolded, and means for lowering the folded mattress-support within the base of the sofa-frame and beneath the seat.

10. The combination, in a sofa-bed, of a mattress-supporting frame having relatively foldable sections, and a leg foldably attached to one of said sections, a member having connection with said leg and the section to which it is attached and automatically operable by a relative movement of the leg and section to engage or release a part of another of said sections when said sections are in predetermined positions of their relative folding movements.

In witness whereof, I have hereunto subscribed my name in the presence of two witnesses.

CHARLES J. KINDEL.
